TURPENTINE PROCESS.

1,124,606.

Specification of Letters Patent. Patented Jan. 12, 1915.

Application filed March 20, 1913. Serial No. 755,734.

To all whom it may concern:

Be it known that I, JOSHUA G. GARDNER, a citizen of the United States, residing at Daytona, in the county of Volusia and State of Florida, have invented new and useful Improvements in Turpentine Processes, of which the following is a specification.

This invention relates to a turpentine process and particularly to the elimination 10 of turpentine from light turpentine bearing materials, such as sawdust, and a simultaneous refining of the eliminated turpentine product.

The primary object of the invention is to 15 economize in the production of refined turpentine by avoiding the operation usually pursued of reëvaporation or a subsequent treatment of the turpentine product exterior of the still and to produce at one operation a highly refined turpentine that is 20 ready for use as taken from the condenser.

In carrying out the improved process the 25 vapors are settled and refined by having the lighter or more volatile portions, or the best turpentine, pass through the condenser without accompanying heavier vapors, which are usually rosin oil and deleterious to the drying properties of turpentine. The 30 improved process is therefore effected solely in the still and condenser and permits the condenser to be disposed at a distance from the still, and by this means the distilling plants are permitted to be placed within a saw mill, for instance, and have the vapors 35 condensed away off from the mill, and whatever heavy distillate may be deposited in the still may also be piped off to a distance from the mill and thus avoid any conflict with insurance companies.

40 This improved process is adapted for application to any turpentine bearing material, but is especially advantageous in treating sawdust as taken from the saw mill without depreciating the effectiveness of the sawdust as a fuel. The process is practically dry as no solvent or eliminating medium other than steam is used, and hence in treating sawdust to extract turpentine therefrom a saving of the valuable product, 45 turpentine, results without subjecting the sawdust to a very moist treatment, and therefore when the sawdust is removed after elimination of the turpentine from the still it will be found practically dry and may be 50 passed along or conveyed to the feeding

point of a furnace or stored in a fuel house in proper condition for immediate use as a fuel.

To assist in carrying out the improved process one form of apparatus is illustrated 60 in the accompanying drawing, wherein:

Figure 1 is a sectional view of a still. Fig. 2 is an enlarged detail section of a portion of the still.

Briefly referring to the structure of the 65 apparatus, the numeral 5 designates the outer body of the still constructed of metal of suitable thickness and having an annular head 6 connected thereto provided with a hinged cap 7 and releasable hook bolts or 70 analogous devices 8 for securing the said cap in closed position. Between the upper edge of the head 6 and the portion of the under side of the cap 8 engaged thereby a tight joint is formed through the medium of 75 a suitable gasket 9, or any other means may be used for effecting a non-leakable association of the cap with the upper edge of the head. Centrally connected to the cap is a steam inlet pipe 10 having a valve 11 to control the flow of the steam into the still. The head 6 has an inner annular ledge or shoulder 12 with an inclined bearing surface to receive a correspondingly shaped rim 13 of a cage or carrier 14 which is normally held 80 suspended within the still and is formed with an imperforate side wall 15 and a perforate bottom 16 which is hinged as shown and adapted to be released to permit the discharge of the contents of the cage or carrier. 85 Between the rim 13 and the shoulder or ledge 12 a suitable non-leakable joint or hydraulic seal 17 is provided, the tightness of the joint or association of the rim 13 with the ledge 12 being effected by the weight of 90 the cage or carrier. To the bottom 18 of the body of the still a drain or outlet pipe 19 is connected and has a suitable valve 20 and a thermometer 21. The side of the body 5 has a vapor outlet pipe 22 connected thereto and 95 communicating with the interior of the still, said latter pipe being provided with a valve 23 and the pipe may be of any length desired and connects with the usual form of condenser 22^a that may be adjacent to or located a distance from the still. Communicating with the body of the still above the pipe 22 is a steam pipe 24 having a valve 25, the steam from this pipe being used to clean 100 out the still or to drive any deleterious ma- 110

2

terial or residuum that may collect on the bottom 18 through the pipe 19 to any distance from the still that may be desired, and by this means the combustible or inflammable substances will be prevented from remaining in the still, with material advantages from a commercial standpoint in complying with the requirements of insurance laws and rules.

- 10 To prepare the apparatus for carrying out the process the cage or carrier 14 is charged or filled with sawdust and inserted in the body 5 of the still. The cap 7 is then closed and secured and the valves 23 and 25 respectively of pipes 22 and 24 are closed and the valve 20 of the outlet pipe 19 opened. The valve 11 of the steam inlet pipe 10 is then opened and a charge of steam is admitted above the top of the cage or carrier 14 and 15 forced downwardly through the contents or sawdust in the latter to drive all air downwardly toward the bottom of the still and out through the pipe 19. This preliminary step of driving out the air from the material treated is very important as it encourages a 20 thorough elimination or extraction of the products of the sawdust and the valve 20 of pipe 19 remains in open condition until the thermometer 21 registers 212° and steam is 25 sus from the pipe 19. The valve 20 is then instantly closed as well as the valve 11 of pipe 10 and the valve 23 of pipe 22 is opened, thereby causing the turpentine laden vapor to rise and pass out through the said 30 pipe 22 to the condenser 22a. It will be understood that the steam permeates the mass of sawdust and a considerable volume of steam, relatively to the capacity of the still or retort, is admitted to the still, and at first 35 the lower temperature of the still when the steam is admitted thereto will correspondingly reduce the temperature of the steam and the degree of temperature indicated by the flow at the pipe 19 may for some little 40 time be below 212°, and the steam is permitted to pass out of the pipe 19 until the retort or still becomes fully heated to 212°, for instance, and when such temperature shows 45 at the outlet pipe 19 the volume of steam 50 within the still or retort will be quite large. It is obvious that the greater pressure of the steam will be in the top of the retort nearest the inlet point therefor, and hence the steam is driven downwardly through the mass of 55 sawdust and as soon as the temperature of 212° is indicated at the outlet pipe 19 the operator will know that the elimination of turpentine from the sawdust will be immediately effected and the valves 11 and 20 will 60 be promptly closed and the valve 23 of pipe 22 will be immediately opened so that the steam within the still may be allowed to escape only by flowing upwardly around the basket or carrier containing the sawdust, and as the steam rises the pressure will be

greater toward the top of the still than at the bottom and the heavier substance eliminated will be promptly gravitated to the bottom of the still; whereas the lighter turpentine vapors of a pure character will escape through the pipe 22 and valve 23 without carrying therewith any deleterious matter. This operation is materially distinguished from the treatment of large pieces of turpentine bearing wood to which a greater heat must be applied and with which solvents must be used in order to extract the turpentine and resinous substances and oils. It is proposed by this process to take out of the sawdust what turpentine may be therein without deteriorating the sawdust as a fuel means, and to make the process as cheap as possible the steps above described are adopted so that any one with a limited knowledge of turpentine extraction may be able to utilize the process in connection with a sawmill, with material advantage in the output of such industry. The space between the cage or carrier 14 is considerably greater in capacity than the outlet pipe 22 and the vapors rising in said space will be held in suspense sufficiently long to cause the heavier portions of the vapors to condense and descend to the bottom of the still body and escape through the pipe 19 as may be desired. In view of the seal or tight joint between the rim 13 of the cage or carrier and the annular ledge 12, the vapors remaining suspended in the space between the body of the still and the cage will be prevented from passing through the joint thus formed and be caused to escape solely through the pipe 22. The steam admitted to the top of the still, as hereinbefore explained, by its pressure is caused to pass fully down through the charge in the cage, first forcing the air out through the perforated bottom 16 and gradually heating the charge until steam shows at the outlet end of the pipe 19 and the escape of the steam is then stopped by closing the valve 20, as hereinbefore stated, and the charge of steam continuing downwardly through the material treated will effect a thorough elimination of the turpentine and other products from the charge. The separation of the heavier vapors by gravitation and condensation within the still results in a refinement of the lighter portion of the vapors or the turpentine and a separation of the rosin oil from the turpentine is positively effected so that when these vapors enter the condenser 22a and pass through the latter, the resultant condensation is pure turpentine which is ready for the market or commercial use without being subjected to further treatment to refine the same. After the charge in the cage 14 has been treated as just explained, the cage is removed from the still and the charge released therefrom and replaced by a new or untreated charge of saw- 130

dust or other material and reinserted in the still when the same process may be carried on. At proper intervals or when found necessary the valves 11 and 23 in pipes 10 and 22 respectively will be closed, and the valves 20 and 25 of pipes 19 and 24 respectively will be opened to admit steam under pressure into the space between the cage 14 and the body of the still and against the bottom 10 of the latter to blow any sediment or residuum remaining in the still out through the pipe 19 to clean out the still and keep the latter in safe condition and in full compliance with the most technical requirements 15 of insurance companies relative to manufacturing plants and especially turpentine still plants. By cleaning out the still as specified liability of firing the still is prevented.

The process may be practised wherever a 20 steam supply is convenient and in view of the economy in the production of refined turpentine or the dual steps of distillation and refinement within the still and without requiring subsequent treatment of the turpentine 25 after it passes off from the condenser, the cost of manufacture of turpentine is materially reduced, and it is obvious that the process may be carried on with advantage in connection with saw mills to 30 treat the sawdust as produced and without deteriorating the sawdust as a practical fuel. The process may be carried on very close to a mill and as no attention is necessary relative to the subsequent refinement of 35 the turpentine product issuing from the condenser, the still or retort may be easily controlled and the process practically carried out with a minimized number of attendants in contradistinction to that class of stills 40 wherein turpentine processes are practised requiring observation and separation of dirt and other products from the turpentine or condensed vapors issuing from the condenser. The use of steam as the eliminating 45 medium without resorting to the application of any other solvent is also important from a standpoint of economy, especially in view of the fact that one steaming or the admission of a predetermined charge of steam to 50 the still or retort effects the distillation of the products from the raw material and also a simultaneous refinement of the turpentine so that the condensed vapors issuing from

the condenser may be immediately used without further refinement.

55

What is claimed is:

1. A process of simultaneously distilling and refining turpentine, consisting in disposing a charge of comminuted terpene bearing material in a retort, injecting a charge 60 of steam through the material to drive out the air therefrom to the exterior of the retort and also to heat the latter and the mass to a turpentine separating degree and preventing the escape of any of the turpentine bearing vapors through the preliminary 65 air escape means and after the retort and the material have reached a temperature at which the turpentine will separate from the material and thereby causing the heavier 70 substances to separate and gravitate from the turpentine bearing vapors while the latter are rising in the retort, and finally permitting the turpentine bearing vapors to escape from the retort and be condensed to 75 produce pure turpentine.

2. The process of simultaneously distilling and refining turpentine, consisting in disposing a charge of comminuted turpentine bearing material in a retort having a 80 closable air vent and steam outlet, injecting a charge of steam downwardly through the material to drive out the air and also to heat the charge of comminuted turpentine bearing material to a degree of turpentine 85 extraction, closing the air outlet and cutting off the injection of steam from the retort when the mass treated and the retort have reached a degree of heat necessary to 90 separate the turpentine from the turpentine bearing material, and finally permitting all of the vapors within the retort to rise in the latter and the heavier portions of the vapors to condense and gravitate by coming in contact with the outer cooler portion of the retort and permitting the lighter pure turpentine 95 vapors to escape from the retort and be condensed to produce refined turpentine.

In testimony whereof I have hereunto set my hand in presence of two subscribing witnesses.
